(57) **CLAIM**

The ornamental design for a container with cap, as shown and described.

DESCRIPTION

FIG. 1 is a three-dimensional perspective view of the container with cap;

FIG. 2 is a front view of the container with cap;

FIG. 3 is a back view of the container with cap;

FIG. 4 is a right side view of the container with cap;

FIG. 5 is a left side view of the container with cap;

FIG. 6 is a top view of the container with cap; and,

FIG. 7 is a bottom view of the container with cap.

The broken line shown in FIG. 7 is for environmental purposes only and forms no part of the claimed design.
